US00D633889S

(12) **United States Design Patent**
Lu

(10) **Patent No.:** US D633,889 S
(45) **Date of Patent:** ** Mar. 8, 2011

(54) **MOBILE PHONE**

(75) Inventor: **Li-Houng Lu**, Tu-Cheng (TW)

(73) Assignee: **Chi Mei Communication Systems, Inc.**, Tu-Cheng, Taipei County (TW)

(**) Term: **14 Years**

(21) Appl. No.: **29/360,142**

(22) Filed: **Apr. 21, 2010**

(30) **Foreign Application Priority Data**

Jan. 7, 2010 (CN) 2010 3 0300413

(51) **LOC (9) Cl.** 14-03

(52) **U.S. Cl.** ..... **D14/138 AD**

(58) **Field of Classification Search** ..... D14/138 R, D14/138 AD, 138 AC, 138 C, 138 G, 191, D14/203.1-203.8, 496, 138 AA, 138 AB, D14/137, 147, 218, 341-347, 247-248; D10/65, 78, 104; D13/168; D18/7; 455/566, 455/575.1, 575.3, 575.4

CLAIM

The ornamental design for a mobile phone, as shown and described.

DESCRIPTION

FIG. 1 is a perspective view of a mobile phone showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines immediately adjacent the claimed areas represent the bounds of the claimed design while all other broken lines are directed to environment and are for illustrative purposes only; the broken lines form no part of the claimed design.

1 Claim, 7 Drawing Sheets
